UNITED STATES PATENT OFFICE.

GEORGE D. EDWARDS, OF EAST ORANGE, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

1,340,942.

Specification of Letters Patent.

Patented May 25, 1920.

Application filed November 28, 1917. Serial No. 204,340.

To all whom it may concern:

Be it known that I, GEORGE D. EDWARDS, a citizen of the United States, residing at East Orange, in the county of Essex and State 5 of New Jersey, have invented certain new and useful Improvements in Signaling Systems, of which the following is a full, clear, concise, and exact description.

This invention relates to electric signaling 10 systems and more particularly to composite telephone and telegraph systems, and has for its principal object elimination of interference between telephonic and telegraphic signals, and more specifically the elimination 15 of telegraphic impulses from the telephonic circuit so that they are not reproduced by the telephone receivers at the various stations of the system. This object is accomplished by the provision of a composite 20 circuit having suitable frequency filtering apparatus arranged in the telephonic portion thereof; the filters being designed to prevent passage of currents of low or telegraphic frequencies but to permit the free 25 passage of currents of the relatively higher or telephonic frequencies.

Another object is to provide a composite 30 telephone and telegraph system having an anti-side tone telephonic circuit in which currents of telephonic frequencies will be reduced in their effect on the telephonic apparatus by proportioning the relative telephonic transmitting and receiving efficiencies of such apparatus so that the net telephonic efficiency is substantially maintained 35 while very greatly decreasing the effect of the telegraphic frequencies in such apparatus. To accomplish this purpose, suitable means are provided to increase the transmitting 40 efficiency of the telephonic apparatus relative to and at the expense of the receiving efficiency so that the decrease in receiving efficiency which effects reception of both telegraphic and telephonic currents 45 in the telephonic apparatus is practically compensated for by the increased telephonic transmitting efficiency which latter does not, however, affect the telegraphic transmitting efficiency.

Another object of the invention is to provide 50 an anti-side tone telephonic circuit wherein the transmitting efficiency may be readily increased, as desired, and an anti-side tone circuit still maintained. To this end telephone sets are provided with suit-

able means operable to increase the flow of current to the transmitter while at the same time maintaining an anti-side tone circuit through the transmitter and receiver of the set.

The drawing illustrates, in diagrammatic form, one application of the invention to a composite system; two stations only being indicated although other stations can be bridged across the line as desired.

The stations, A and B, shown, are each provided with both telegraphic and telephonic apparatus, the telegraphic apparatus being indicated in the upper rectangles 1 and 2 respectively, while the telephonic apparatus is indicated in the lower rectangles 3 and 4 respectively. A metallic line 5-5' is shown as extending between the various stations, but a grounded return may be used if desired.

The telegraphic apparatus shown consists of a telegraphic key 6, a relay 7, and a local sender 8 controlled by the relay 7 in the usual manner. A circuit connection including a condenser 9 extends about the key 6 and relay 7 to provide a path for the passage of fluctuating telephonic currents, the condenser serving to force the telegraphic currents through the windings of relay 7 in the usual manner. The key 6 is shown as 80 open in the drawing, but would ordinarily be closed unless it were being operated in the transmission of telegraphic signals. The windings of relay 7 are preferably of relatively high impedance while the condenser 9 is preferably of relatively low capacity so that even with the key 6 closed only a small percentage of telephonic currents can pass through the windings of the relay 7, while by far the greater percentage will pass freely 85 through the condenser 9. Such telephonic currents as may pass through the windings of the relay 7 will not operate this relay, due to the relatively low strength of current resulting from telephonic operation of 90 the system. The condenser 9 is preferably made sufficiently low in capacity so that the telegraphic currents will be forced through the relay 7 instead of being shunted around it through the condenser shunt.

Battery for operating the telegraphic portion of the system is arranged between the lines 5 and 5', a battery 10 being shown at each station in the present case since more satisfactory results are obtained thereby; al-

110

though a common battery source can be used if desired. A retardation coil 11 is located in the circuit between each of the batteries 10 and the line 5 to regulate the battery supplied to the telegraphic circuit, and to prevent the bridging loss to the telephone circuit which the battery would otherwise cause.

The telephone apparatus shown in the rectangles 3 and 4 is arranged to provide an anti-side tone set and comprises an induction coil 12, the secondary of which is included in a telephonic branch circuit extending between the line wires 5 and 5', and including a condenser 13 of relatively low capacity between the secondary of the coil 12 and the line 5. The coil 12 and condenser 13 are proportioned in such a way that separately and in combination they are inefficient in transmitting the low frequency telegraphic currents impressed upon the line, but highly efficient in transmitting the relatively higher frequency telephonic currents. In this way the coil 12 and condenser 13 serve to filter out the telegraphic frequencies while efficiently transmitting currents within the usual range of telephonic frequencies.

A transmitter 14 is arranged in a circuit in series with the primary winding of the coil 12, which circuit also includes in series therewith one winding of a second induction coil 15, the other winding of which furnishes operating current to a telephone receiver 16 arranged in a closed series circuit with the coil winding and a condenser 17. The coil 15, like the coil 12, is also designed to have a low mutual impedance at low frequencies, while the condenser 17 is preferably of relatively low capacity so that the coil 15 and condenser 17 will serve to attenuate and to sensibly extinguish low frequency currents, as hereinafter described.

In order to provide for the maximum efficiency of telephonic systems while at the same time filtering out currents within the usual range of telegraphic frequencies, the coils 12 and 15 are preferably so designed that the mutual impedance of each of the coils is low at low frequencies, although the coefficient of coupling is made as near unity as possible. This arrangement will be best understood from a consideration of the following formulæ relating to impedance conditions.

$$(7) \quad Zm = k \sqrt{\sqrt{R_1^2 + (2\pi f L_1)^2} \times \sqrt{R_2^2 + (2\pi f L_2)^2}}$$

which represents the mutual impedance between the two coils of the transformer independent of any condenser in series with one of the coils.

Considering equation (7) it is evident that if k is made low, the result will be inefficient transformation and transmission at

These formulæ are:

$$(1) \quad Z = \sqrt{R^2 + X^2}$$

$$(2) \quad X \text{ (with negligible capacity)} = 2\pi f L$$

$$(3) \quad X \text{ (with appreciable capacity)} =$$

$$2\pi f L - \frac{1}{2\pi f C}$$

$$(4) \quad Zm = k \sqrt{Z_1 \times Z_2}$$

in which Z represents impedance, R , effective resistance, X , reactance, f , the frequency in complete cycles per second, L , the inductance, C , the capacitance, Zm , the mutual impedance of the transformer, k , the coefficient of coupling between the two windings thereof, and Z_1 and Z_2 , the self-impedances of the respective windings of the transformer.

The terms above given are used in accordance with the meanings outlined in the present standardization rules of the American Institute of Electrical Engineers.

From equation (4) it is evident that Zm is made smaller or larger according as any one or more of k , Z_1 or Z_2 are decreased or increased. Equation (2) is applicable to a coil winding for all practical purposes inasmuch as the capacity factor

$$\left(\frac{1}{2\pi f C} \right)$$

of coil windings, such as used in induction coils for such use, is so small as to be negligible.

Substituting in equation (1) the valuation of X , given in equation (2), gives equation

$$(5) \quad Z = \sqrt{R^2 + (2\pi f L)^2}$$

which represents the self-impedance of a single one of the transformer coils; while substituting the valuation of X , given in equation (3) in equation (1) gives equation

$$(6) \quad Z = \sqrt{R^2 + \left(2\pi f L - \frac{1}{2\pi f C} \right)^2}$$

which represents the self-impedance of that part of the circuit including a coil winding and a condenser in series therewith.

Applying different numerals to equation (5) to distinguish the different coils of the transformer, and substituting in equation (4), gives equation

any and all frequencies so that it is, therefore, preferable to design the two windings of the coil so that their impedances Z_1 and Z_2 will be relatively low at low frequencies in order that Zm will be low under these conditions and so attenuate and sensibly extinguish currents of frequencies below those

which it is desired to have telephonically audible.

Referring to equation (7) it will be seen that either or both the effective resistance, 5 or inductance of either one, or both of the windings can be so proportioned as to make Z_m so low as to prevent transmission of currents of telegraphic frequencies through the coils and circuits associated therewith to 10 the receiver 16, while at the same time Z_m will be sufficiently high at telephonic frequencies that currents of such frequencies would be efficiently transmitted throughout the telephonic portion of the system. This 15 results from the frequency factor, f , in equation (7), inasmuch as the other factors remaining constant the mutual impedance Z_m of the coils is a direct function of the frequency of the current passing therethrough. 20 Any circuit which includes one of the windings of the coil 12 or 15 in series with one of the condensers 13 or 17 respectively has the self-impedance of such part of the circuit represented by equation (6) 25

$$Z = \sqrt{R^2 + \left(2\pi fL - \frac{1}{2\pi fC}\right)^2}.$$

Inasmuch as the efficiency of transmission depends, to a great extent, on the impedance 30 encountered in the circuits and apparatus thereof, it will be apparent that the addition of a condenser in series with one of the windings of coils 12 and 15 is a further element effecting attenuation of currents of low 35 frequency inasmuch as the capacity factor

$$\left(\frac{1}{2\pi fC}\right)$$

40 of the condenser in equation (3) coöperates with the inductance factor $(2\pi fL)$ thereof to produce a marked change in the reactance of the circuit rapidly as the frequency increases or decreases; for example, at a 45 frequency of 20 cycles per second X would be

$$40\pi L - \frac{1}{40\pi C},$$

while at 900 cycles per second X would be

$$1800\pi L - \frac{1}{1800\pi C}.$$

In these equations it will also be seen that by using a condenser of relatively low capacity the rate of change in the factor

$$\frac{1}{2\pi fC}$$

60 will be more rapid under changes of frequency within the range encountered than where a condenser of relatively greater capacity is used.

From the foregoing it will be apparent that currents of low frequency will be attenuated in passing through that part of

the telephone leg of the circuit which includes one winding of the coil 12 in series with the condenser 13, while further attenuation is accomplished, due to the low mutual impedance of the coil 12, at low frequencies. 70 Any part of such low frequency currents which are not extinguished by the condenser 13 and coil 12 would flow through the primary winding of the coil 15 which, having a low mutual impedance at low frequencies, 75 would still further extinguish currents of such low frequencies. The condenser 17 in series with the secondary winding of the coil 15 would also increase the low frequency impedance of the receiver circuit 80 so as to practically extinguish such low frequency currents as might pass the coil 15 or to reduce them to such a low strength that the receiver 16 would not function to translate such currents into audible sounds. 85

The reactance of the condenser 17 in the receiver circuit at talking frequencies may be practically annulled by that of the receiver 16 and of the receiver induction coil 15; the receiver 16 preferably being of relatively high impedance. "Telegraphic frequencies" as used in this case is intended to apply to frequencies generated in the course of ordinary key transmission together with the lower harmonics of such frequencies 95 which would ordinarily not exceed 100 cycles per second; while "telephonic frequencies" as here used is intended to apply to frequencies beginning as low as 200 cycles per second and running up to the limit of 100 audibility.

Referring now to the transmitter circuit, the transmitter 14 is included in a local battery circuit. This circuit leads from one side of a local battery 18 through the transmitter 14, conductor 19, thence normally by conductors 20 and 21 through a non-inductive balancing resistance 22 and conductor 23 to an intermediate point of the primary winding of the coil 12 and through the lower portion of this winding to the other side of the battery 18. A parallel circuit is also normally provided beginning at conductor 21 and extending through a manually operated key 24 and the normal contact 115 thereof, conductors 25 and 26, primary winding of coil 15, conductor 27, and upper portion of the primary winding of coil 12 to conductor 23. A second non-inductive resistance 28 of relatively greater value than 120 resistance 22 is connected between conductors 20 and 26 but is normally shunted out by the low resistance path from conductor 19 through conductor 20, key 24 in engagement with its normal contact, and conductor 125 25 to conductor 26. This arrangement furnishes a circuit which is advantageous in preventing a speaker hearing his own voice too strongly, and also serves to prevent currents set up in a transmitter by extraneous 130

noises and vibrations in the vicinity thereof being transmitted to the local receiver with sufficient strength to set up audible side tones in the receiver. This result is due 5 to the fact that the current variations produced by the local transmitter 14 flowing through the lower portion of the primary of the induction coil 12 induced currents of counter-electromotive force in the upper 10 portion of the primary of the coil 12 of such value and direction as to practically neutralize the currents which would otherwise flow through the local receiver induction coil 15; through the parallel circuit normally existing about the resistance 22 in 15 the transmitter circuit previously traced. Under these conditions practically no transmitting current flows through the primary of the receiver induction coil 15 during 20 transmission at that station. It will be noted that a greater number of turns of the primary of the coil 12 are included in the local transmitting circuit than in the local receiving circuit. The purpose of this arrangement is to obtain an increased telephonic transmitting efficiency and a somewhat less relative receiving efficiency while 25 still preserving the anti-side tone features of the set. The decreased receiving efficiency serves to reduce the strength of both 30 telegraphic and telephonic currents received at the primary of the receiver induction coil 15. This reduction in the case of telephonic currents is offset by the increased telephonic transmitting efficiency but does not increase 35 the telegraphic currents, and thus effects a reduction of the telegraphic currents received in the telephonic circuit without reducing the net telephonic efficiency over a 40 set having identical transmitting and receiving efficiencies.

When telephonic communication is being carried on under noisy conditions at either the transmitting or receiver stations, it is 45 desirable that the parties talking be provided with means whereby they can temporarily increase the transmitting efficiency of their respective telephone sets. To accomplish this result, and at the same time preserve the anti-side tone feature of the 50 circuit, the circuit is so arranged that by engaging the key 24 with its alternate contact the resistance 22 is short-circuited by the conductor 29 and the resistance 28 connected in series with the primary of the coil 15. The shunting out of resistance 22 lowers 55 the resistance of the transmitter circuit and increases the currents supplied by the battery 18 to the transmitter 14 and at the same time prevents any appreciable current 60 from the battery 18 reaching the coil 15. The resistances 22 and 28, together with the other apparatus in the circuits, are so proportioned that while the receiving efficiency 65 is decreased and the transmitting

efficiency increased under these conditions, the receiving efficiency will still be great enough so that any answers or interruptions made by the party at the receiving station will be clearly audible at the receiver 16 of 70 the transmitting station.

During telephonic connection, fluctuating voice currents originate at one station, and passing through the primary of the coil 12 at that station, induce corresponding currents in the secondary of the coil 12 thereat. These induced currents being of telephonic frequency will pass freely through the condenser 13 to the conductor 30 and through the condenser 9 of the telegraph set at the 75 transmitting station, over the line 5; through the condenser 9 of the telegraph set, conductor 30, condenser 13 and secondary of the coil at the receiving station, to the return line 5' leading to the lower side of the secondary of the coil 12 at the transmitting station. Telephonic currents passing through the secondary of the coil 12 at the receiving station induce corresponding currents in the primary thereof. The currents induced in 80 the upper portion of the primary of this coil flow through the primary of the receiver induction coil and normally through the balancing resistance 22 to the junction of the upper and lower portions of the primary winding of the coil 12. When the key 24 is operated to engage the conductor 29, the balancing resistance 22 is shunted out, while the higher resistance 28 is connected 85 in series with the primary of the coil 15, thereby diminishing the strength of current flowing therethrough to reduce the receiving efficiency, but at the same time increasing the transmitting efficiency of that station, as previously described.

In practice, the key 24 at a station is operated only when the called party thereat desires to temporarily increase the transmitting efficiency while actually talking to another party, and this key would normally be released when the party called was replying, although the receiving efficiency at the original transmitting station is sufficient so that the party thereat can understand interruptions from other stations even though his key 110 24 be depressed. On releasing the key, the receiving efficiency is increased to its normal condition, while the transmitting efficiency is at the same time diminished to its normal value, which, however, is sufficient to operate 115 satisfactorily under normal transmitting conditions.

What is claimed is:

1. In an electrical signaling system, a telephonic receiver, a telephonic transmitter, 125 a transformer having a plurality of windings inductively associated, a source of direct current, a circuit including the transmitter and source of current in series with a portion of one of the transformer windings, a 130

second circuit in parallel with the first circuit including the source of current and another portion of the transformer winding included in the first circuit, a telephone receiver operatively associated with the parallel circuit, and a third circuit including another of the transformer windings.

2. In a combined telephone and telegraph system, a telephonic receiver, a plurality of condensers, two transformers each having a plurality of windings inductively associated, a circuit including one winding of one of said transformers arranged in series with one of said condensers and with said receiver, another winding of such transformer being arranged in series with one winding of the other transformer, and a second circuit including another winding of such other transformer arranged in series with another of said condensers; the impedances of said windings and the capacitances of said condensers being so proportioned that the combined mutual impedances of said transformers and condensers are low at telegraphic frequencies and relatively higher at telephonic frequencies, while the self-impedances of said circuits are relatively high at low frequencies and relatively low at high frequencies, whereby currents of telegraphic frequencies are practically extinguished before reaching said telephonic receiver, while currents of telephonic frequencies are transmitted to said receiver with but relatively slight attenuation or sensible extinguishment.

3. In a telephone system, a transmitter, a transformer having a plurality of windings inductively associated, a source of current, a resistance, a circuit normally including said transmitter, the source of current and resistance in series with a portion of one of said transformer windings; a shunt circuit about a portion of said first circuit and including another portion of the transformer winding included in said first circuit, a telephone receiver operatively associated with said shunt circuit, and means to effectively remove said resistance from said first circuit to change the strength of current supplied to said transmitter.

4. In a telephone system, a transmitter, a transformer having a plurality of windings inductively associated, a source of current, a resistance, a circuit normally including said transmitter, the source of current and resistance in series with a portion of one of said transformer windings; a shunt circuit about a portion of said first circuit and including another portion of the transformer winding included in said first circuit, a telephone receiver operatively associated with said shunt circuit, and means to effectively remove said resistance from said first circuit to increase the strength of current supplied to said transmitter.

5. In a telephone system, a transmitter, a transformer having a plurality of windings inductively associated, a source of current, a resistance, a circuit normally including said transmitter, source of current and resistance in series with a portion of one of said transformer windings; a shunt circuit about a portion of said first circuit and including another portion of the transformer winding included in said first circuit, a telephone receiver operatively associated with said shunt circuit, means to effectively remove said resistance from said first circuit to change the strength of current supplied to said transmitter, and means to maintain said shunt circuit on effective removal of said resistance from said first circuit.

6. In a telephone system, a transmitter, a transformer having a plurality of windings inductively associated, a source of current, a resistance, a circuit normally including said transmitter, source of current and resistance in series with a portion of one of said transformer windings; a shunt circuit about a portion of said first circuit and including another portion of the transformer winding included in said first circuit, a receiver operatively associated with said shunt circuit, a second resistance, means to effectively remove said first resistance from said first circuit, and means to effectively include said second resistance in said shunt circuit on the effective removal of said first resistance from said first circuit.

7. In a telephone system, a transmitter, a transformer having a plurality of windings inductively associated, a source of current, a first resistance, a circuit normally including said transmitter, source of current and resistance in series with a portion of one of said transformer windings, a shunt circuit about a portion of said first circuit and including another portion of the transformer winding included in said first circuit, a receiver operatively associated with said shunt circuit, a second resistance of greater value than said first resistance, means to effectively remove said first resistance from said first circuit, and means to effectively include said second resistance in said shunt circuit on the effective removal of said first resistance from said first circuit.

8. In a combined telephone and telegraph system, a plurality of telephonic stations, telephonic transmitting and receiving apparatus at each of said telephonic stations, a plurality of telegraphic stations, telegraphic transmitting and receiving apparatus at each of said telegraphic stations, a common conductor to carry both telegraphic and telephonic currents between said stations, said telephonic apparatus comprising a transmitter, a receiver, an anti side-tone circuit including said transmitter and receiver, and means included in said circuit increasing

- ing the transmitting efficiency and decreasing the relative receiving efficiency of the circuit; whereby both telephonic and telegraphic currents received at a receiving station are diminished, while the increased efficiency of telephonic transmission substantially compensates for the decreased telephonic receiving efficiency without affecting the telegraphic transmitting efficiency.
- 10 9. In a combined telephone and telegraph system, a plurality of telephonic stations, telephonic transmitting and receiving apparatus at each of said telephonic stations, a plurality of telegraphic stations, telegraphic transmitting and receiving apparatus at each of said telegraphic stations, a common conductor to carry both telephonic and telegraphic currents between said stations, said telephonic apparatus comprising a transmitter, a receiver, a transmitting circuit, a receiving circuit, said circuits being associated to provide an anti side-tone circuit, and a transformer having a plurality of windings, one of said windings being connected with said conductor and another of said windings having different portions thereof included respectively in said transmitting and receiving circuits, the proportions of said winding included in the respective transmitting and receiving circuits being such that the transmitting efficiency of said transmitting circuit is increased relative to the receiving efficiency of said receiver circuit; whereby both telephonic and telegraphic currents received in said telephonic receiving circuit are of diminished magnitude while the increased efficiency of said transmitting circuit substantially compensates for the decreased telephonic receiving efficiency of said receiving circuit without affecting the telegraphic transmitting efficiency.
- 15 10. In a telephone system, a transmitter, a source of direct current, a circuit including said transmitter and source of current, a second circuit in parallel with the first circuit including said source of current, a telephone receiver operatively associated with said second circuit, and means independent of the transmitter to change the relative resistance of said first and second circuits to increase the strength of current supplied from said source of current to said transmitter and to decrease the strength of current supplied from said source of current to said second circuit during the operative association of said transmitter and receiver.
- 20 11. In a telephone system, a transmitter, a source of direct current, a first circuit including the transmitter and source of current, a receiver, a second circuit in parallel with the first circuit including the transmitter and source of current and operatively associating the receiver with the transmitter, and means independent of the transmitter to increase the relative strength of current sup-

plied to one of these circuits from the source of current during the operative association of the transmitter and receiver when the relative strength of current supplied to the other of these circuits is decreased.

70 12. In a telephone system, a transmitter, a source of direct current, a first circuit including the transmitter and source of current, a receiver, a second circuit including the transmitter and source of current operatively associating the receiver with the transmitter, and means independent of the transmitter to decrease the relative strength of current supplied to the second circuit from the source of current when the relative strength of current supplied to the first circuit from the source of current is increased during the operative association of the transmitter and receiver.

75 13. In a telephone system, a transmitter, a source of direct current, a first circuit including the transmitter and source of current, a receiver, a second circuit including the transmitter and source of current operatively associating the receiver with the transmitter, and means independent of the transmitter regulating the relative strength of current supplied from the source of current to each of the two circuits operable to simultaneously decrease the relative strength of current from the source supplied to the second circuit when this means is operated to increase the relative strength of current from the source supplied to the first circuit during the operative association of the transmitter and receiver.

80 14. In a telephone system, a transmitter, a source of direct current, a first circuit including the transmitter and source of current, a receiver, a second circuit including the transmitter and source of current operatively associating the receiver with the transmitter, means associated with the two circuits regulating the normal division of current from the source of current between the two circuits during the operative association of the transmitter and the receiver, and means to change the association of the regulating means with the two circuits to simultaneously increase the relative strength of current in one of the circuits and to decrease the relative strength of current in the other of the circuits.

85 15. In a telephone system, a transmitter, a source of direct current, a resistance, a first circuit including the transmitter, source of current and resistance therein, a receiver, a second circuit in parallel with the first circuit including the source of current therein operatively associating the receiver with the transmitter, and means operable during the operative association of the receiver and transmitter to effectively remove the resistance from the first circuit while preserving the continuity of both of the circuits to increase the rela-

- tive strength of current from the source of current in the first circuit as compared to the strength of current in the second circuit.
- 5 16. In a telephone system, a transmitter, a source of direct current, a first and a second resistance, a first circuit including the transmitter, source of current and the first resistance therein, a receiver, a second 10 circuit in parallel with the first circuit including the source of current therein and operatively associating the receiver with the transmitter, and means operable during the operative association of the receiver and 15 transmitter to effectively remove the first resistance from the first circuit and to effectively include the second resistance in an individual portion of the second circuit while preserving the continuity of both circuits to increase the strength of current 20 from the source of current in the first circuit and to decrease the strength of current in the second circuit.
17. In a telephone system, a transmitter, 25 a source of direct current, a transformer having a plurality of windings, a first circuit including the transmitter, source of current and a portion of one of the windings, a telephone receiver, a second circuit 30 in parallel with the first circuit including the source of current and another portion of said one of the windings and operatively associating the receiver with the transmitter, and means to inversely vary the relative 35 strength of current supplied from the source of current to the respective portions of said one of the windings included in the respective circuits during the operative association of the transmitter and receiver.
- 40 18. In a telephone system, a transmitter member, a source of direct current, a transformer having a plurality of windings, a circuit including the transmitter member, source of current and a portion of one of the windings therein, a telephonic receiver 45 member, a second circuit in parallel with the first circuit including the source of current and another portion of said one of the windings and operatively associating the receiver member with the transmitter member, and means to inversely vary the relative strength of current from the source of current to the members through their respective portions of said one of the windings during the operative association of the 50 members.
19. In a telephone system, a transmitter, a source of direct current, a transformer having a plurality of windings, a circuit including the transmitter, source of current 55 and a portion of one of the windings therein, a receiver, a second circuit in parallel with the first circuit including the source of current and another portion of said one of the windings and operatively associating the 60 receiver with the transmitter, and means to simultaneously increase the relative strength of current from the source of current supplied to the transmitter through the portion of the winding included in the first circuit 65 and to decrease the relative strength of current supplied to the receiver through the portion of the winding included in the second circuit during operative association of the 70 transmitter and receiver. 75

In witness whereof, I hereunto subscribe my name this 26th day of November, A. D., 1917.

GEORGE D. EDWARDS.
